UNITED STATES PATENT OFFICE

166,316

LAMP

John Juergens, McHenry, Ill.

Application July 27, 1951, Serial No. 16,050

Term of patent 14 years

(Cl. D48—20)

To all whom it may concern:

Be it known that I, John Juergens, a citizen of the United States, residing at McHenry, McHenry County, State of Illinois, have invented a new, original, and ornamental Design for a Lamp, of which the following is a specification, reference being had to the accompanying drawing, forming a part hereof:

Fig. 1 is a perspective view of a lamp, showing my new design;

Fig. 2 is a front elevational view of the lamp; and

Fig. 3 is a front elevational view of the lamp in a different position of adjustment.

I claim:

The ornamental design for a lamp, as shown.
JOHN JUERGENS.
